UNITED STATES PATENT OFFICE.

ERNEST H. PINKERTON, OF HARLINGEN, TEXAS.

GRAVE-MARKER MOLD.

Application filed May 31, 1927. Serial No. 195,491.

This invention relates to molds, and has for its object to provide, in a manner as hereinafter set forth, a new, novel and improved device of such class for molding grave markers, of cruciform contour, from reinforced concrete or other desirable material.

A further object of the invention is to provide, in a manner as hereinafter set forth, a sectional mold capable of being expeditiously set in molding position and conveniently removed from the molded article when occasion requires.

Further objects of the invention are to provide, in a manner as hereinafter set forth, a mold for the purpose referred to which is simple in its construction and arrangement, strong, durable, compact, thoroughly efficient in its use, conveniently assembled and disassembled, and comparatively inexpensive to manufacture.

With the foregoing and other objects in view the invention consists of the novel construction, combination and arrangement of parts, as hereinafter more specifically described, and illustrated in the accompanying drawings, wherein is shown a preferred embodiment of the invention, but it is to be understood that changes, variations and modifications can be resorted to which fall within the scope of the claims hereunto appended.

In the drawings wherein like reference characters denote corresponding parts throughout the several views:

Figure 1 is an inverted plan of a mold, in set position, in accordance with this invention.

Figure 2 is a fragmentary view in side elevation of a mold when in set position.

Figure 3 is an end view of the mold when in set position.

Figure 4 is a longitudinal sectional view of the mold containing the reinforced material which is to be molded.

Figure 5 is a top plan view of the mold when in set position and containing the reinforced material which is to be molded.

Figure 6 is a section on line 6—6 Figure 5.

Figure 7 is a section on line 7—7, Figure 5 and further illustrating two of the sections 50 of the mold in dotted lines swung to open position.

Figure 8 is a section on line 8—8 Figure 5.

Figure 9 is a perspective view of an article formed by a mold in accordance with this invention.

The mold comprises a bottom member of

cruciform shape provided with a stem 1 and a head 2 formed with an upset portion 3 of rectangular contour and provided with inwardly extending inclined sides 4 which terminate in the upset portion 3. The inclined walls 4 are spaced from the edges of the head 2.

The mold further includes a pair of wall forming members 5, 6 which are of oblong contour and hollow. The members 5 and 6 are of the same width as the stem 1 of the bottom member, but are of materially greater height than the thickness of said stem 1. The wall forming members 5 and 6 are hinged to the stem 1, at opposite sides thereof, and the hinges employed for connecting the members 5 and 6 to the stem 1 are indicated at 7. The members 5 and 6 are of the same length as the length of the stem 1 and abut against the inner side edges of the head 2. The outer side faces of the members 5 and 6 are flush with the ends of the head 2.

The mold further includes a wall forming member 8 of the same length as the length of the head 2. The member 8 is of oblong contour and hollow and is of the same height as the height of either of the wall forming members 5, 6. The wall forming member 8 is hinged to the head 2, and the hinges are indicated at 9. The hinges 7 and 9 are secured to the lower faces of the wall forming members 5, 6 and 8 and to the lower face of the head 2 and stem 1. The member 8 is of less width than the width of either 90 of the members 5, 6.

The mold further includes latching plates 10, 11 and 12 and which also provide wall forming members. The latching plates are of the same height as the height of the members 5, 6 and 8. One end of the member 8 is provided with a keeper 13 which for a portion of its length is offset and opposes the head 2, but is spaced therefrom. The inner end of the member 5 has secured thereto a keeper 14, which has a portion of its length offset and opposes and is spaced from the head 2. The keepers 13 and 14 are arranged in alignment, but oppositely disposed.

The other end of the member 8 has secured thereto a keeper 15 which has a portion of its length offset and opposes and is spaced from the head 2. The inner end of the member 6 is provided with a keeper 16 which has a portion of its length offset and opposes and is spaced from the head 2. The keepers 15 and 16 are arranged in alignment.

but are oppositely disposed with respect to each other. The inner sides of the outer ends of the members 5, 6 are provided with keepers 17, 18 and each of which has a portion of its length offset and spaced from that member to which it is secured. The keepers 17 and 18 are arranged in alignment but are oppositely disposed with respect to each other. The plate 10 associates with the 10 keepers 13 and 14, for latching the members 5 and 8 and to provide a wall of the mold. The plate 11 associates with the keepers 15 and 16 for latching the members 8 and 6 and further for forming another wall of the 15 mold. The plate 12 associates with the keepers 17 and 18 for latching the members 5 and 6 and further provides another wall of the mold. The several keepers referred to are of the same height as the height of the 20 members 5, 6 and 8. When the latching plates are in position with respect to the members 5, 6 and 8 and head 2 the mold is set up to provide a molding cavity of cruciform contour to mold an article consisting 25 of a head 19, provided with a cavity 20 in its front face and integral with the head 20, centrally thereof, is a stem 21, of a greater length than the width of the head. The article, such as grave marker, shown in Figure 30 9, is formed preferably of reinforced concrete, but any suitable material can be employed to provide the body of the marker.

If desired when the marker is molded, the bottom of the cavity 20, can be provided with 35 any suitable inscription or design and if it be desired to provide the bottom of the concavity or recess 20 with an inscription or design the upper face of the upset 3 of the bottom member will be provided with suitable impressing devices, corresponding to the design or inscription desired, and which are indicated at 22 in Figure 4.

When molding the marker a portion of the concrete is placed within the molding 45 cavity formed by the members 5, 6 and plate 12 and after a portion of the concrete has been placed in such part of the cavity metallic bars or reinforcement, as indicated at 23 are positioned. An additional quantity of 50 concrete is then poured into the entire molding cavity and arranged above the upset portion 3, as well as being spaced therefrom, is a foraminous reinforcing member 24 and extending lengthwise of the molding cavity are 55 reinforcements in the form of metallic bars 25. An additional quantity of concrete is then poured into the molding cavity, after which metallic reinforcements 26 are positioned 60 therein. The molding cavity is then completely filled with the concrete material and squared off with respect to the upper faces of the members 5, 6 and 8 and plates 10, 11 and 12. The material is allowed to set until 65 it becomes hardened, after which the latching plates are removed and the mem-

bers 5, 6 and 8 swung clear of the molded article and the latter can then be removed.

The foraminous reinforcement 20 is substantially coextensive with that part of the molding cavity formed by the inner ends 70 of the members 5, 6, the inner side of the member 8 and the latching plates 10, 11. The reinforcements 25 and 26 are of a length to extend from a point in close proximity to the member 8 to the latching plate 12. The 75 reinforcing members 23 are of a length substantially equal to the length of the stem 21. The rods which are employed for reinforcing purposes, are arranged in superposed relation, see Figure 7.

80 The markers preferably are to be molded without any inscription, and when an inscription is desired, it can be readily applied by using the means heretofore referred to for such purpose with the addition of fresh 85 cement in connection with the mold.

It is thought the many advantages of a mold, in accordance with this invention, and for the purpose set forth, can be readily understood, and although the preferred embodiment of the invention is as illustrated and described, yet it is to be understood that changes in the contour of the molding cavity and also in the details of construction can be had which will fall within the scope of 95 the invention as claimed.

What I claim is:

1. A mold comprising a bottom member including a head and a stem, wall forming members hinged to opposite sides of said stem, co-extensive therewith and opposing the inner side of the head, a wall forming member hinged to the outer side of the head, said wall forming members extending above said bottom member, keepers carried by said wall forming members, and combined latching and wall forming plates engaging with said keepers for connecting the wall forming members in position with respect to the bottom member to provide a molding cavity. 110

2. A mold comprising a bottom member including a head and a stem, wall forming members hinged to opposite sides of said stem, co-extensive therewith and opposing the inner side of the head, a wall forming member hinged to the outer side of the head, said wall forming members extending above said bottom member, keepers carried by said wall forming members, and combined latching and wall forming plates 115 engaging with said keepers for connecting the wall forming members in position with respect to the bottom member to provide a molding cavity, said bottom member having its head provided with an upset portion. 125

3. A mold comprising a bottom member including a head and a stem, wall forming members hinged to opposite sides of said stem, co-extensive therewith and opposing the inner side of the head, a wall forming 130

- member hinged to the outer side of the head, said wall forming members extending above said bottom member, keepers carried by said wall forming members, and combined latching and wall forming plates engaging with said keepers for connecting the wall forming members in position with respect to the bottom member to provide a molding cavity, said head being rectangular, and the wall forming members hinged to the stem extending at right angles with respect to the wall forming member hinged to the head.
4. A mold comprising a bottom member including a head and a stem, wall forming members hinged to opposite sides of said stem, co-extensive therewith and opposing the inner side of the head, a wall forming member hinged to the outer side of the head, said wall forming members extending above said bottom member, keepers carried by said wall forming members, and combined latching and wall forming plates engaging with said keepers for connecting the wall forming members in position with respect to the bottom member to provide a molding cavity, the said wall forming member hinged to the head being of the same length as the length of the head, said head being rectangular, and the wall forming members hinged to the stem extending at right angles to the wall forming member hinged to the head and of greater length than the length of the latter.
- 35 5. A mold comprising a bottom member including a head and a stem, wall forming members positioned at opposite sides of the stem, hinges secured to the bottoms of said wall forming members and to the lower face of said stem for connecting said wall forming members and stem together, said wall forming members having their inner ends opposing the inner side of said head, a wall forming member opposing the outer side of said head, hinges secured to the lower face of the head and to the lower face of the last mentioned wall forming member for connecting the latter to the head, keepers carried by the ends of the wall forming members hinged to the stem, keepers carried by the ends of the wall forming member hinged to the head, and combined latching and wall forming plates coacting with said keepers for connecting the wall forming member in position with respect to the bottom member to provide a molding cavity.
6. A mold comprising a bottom member, independent wall forming members hinged to the sides and one end of the bottom member, keepers secured to the ends of the wall forming members hinged to one end of the bottom member, a keeper secured to each end of a wall forming member hinged to a side of the bottom member, and combined latching and wall forming plates coacting with said keepers to connect the wall forming members together and to provide in connection with these latter and said bottom member a molding cavity, said plates positioned at the sides and the other end of the bottom member.
7. A mold comprising a bottom member, independent wall forming members hinged to the sides and one end of the bottom member, keepers secured to the ends of the wall forming members hinged to one end of the bottom member, a keeper secured to each end of a wall forming member hinged to a side of the bottom member, and combined latching and wall forming plates coacting with said keepers to connect the wall forming members together and to provide in connection with these latter and said bottom member a molding cavity, said plates positioned at the sides and the other end of the bottom member, said wall forming members of a height to extend a substantial distance above said bottom member, and said plates and keepers of the same height as said wall forming members.

In testimony whereof, I affix my signature hereto.

ERNEST H. PINKERTON.
